UNITED STATES PATENT OFFICE.

AUSTIN HOPKINSON, OF AUDENSHAW, ENGLAND.

BELT CONVEYER.

Application filed November 27, 1926, Serial No. 151,190, and in Great Britain December 3, 1925.

The invention relates to belt conveyers, and more particularly to means for maintaining the roller frames in their correct positions without the provision of a rigid 5 longitudinal framing.

According to the invention, the roller frames are held in position by tightening a flexible rope, band or chain passing through clamping devices carried by the said frames, 10 but are free to be moved when the rope or its equivalent is slackened.

In one form of the invention the rope or the like passes through a curved channel in a clamping device carried by each roller 15 frame, so that a bight is formed in the said rope.

In a modified construction each roller frame carries pins by which a bight is formed in the rope.

The device is more particularly useful 20 when applied to portable conveyers for mining or other purposes in which the direction of the path of the conveyer may require adjustment from time to time.

In the accompanying drawings which illustrate examples of means according to the 25 invention for holding the roller frames in position—

Fig. 1 is a side and Fig. 2 an end view 30 in elevation of a section of the conveyer; Figs. 3 and 4 show on a larger scale the device for clamping the rope; Figs. 5 and 6 show a modified clamping device, and Figs. 7 and 8 a further modification.

Referring to Figs. 1-4, 1 denotes the vertical frames carrying the upper rollers 2, the lower rollers 3 and the curving rollers 4 for imparting, if desired, a trough-shaped 35 form to the conveyer band 5.

Each post carries also, in the example illustrated at the level of the axis of the upper rollers, on the outside a clamping device or cleat 7 provided with a longitudinal channel 8 curved in the vertical plane through which 40 the rope 9 is passed and in which it forms a bight.

At the front and back edges 10 and 11 of the clamp the rope is seated in an upwardly 45 extending recess 12 and at the centre 13 of the clamp in a downwardly extending recess 14.

In the modification shown in Figs. 5 and 6 the rope 9 is passed through a curved channel 15 provided in a lug 16 of each post 1.

In the arrangement shown in Figs. 7 and 8, three pins 17 with disc-shaped heads 18

are arranged, so that a bight is formed in the rope as it passes over the two lower pins and below the upper pin.

In all these modifications when the rope 60 is tightened, the bight tends to straighten out and pressure is applied at three points of the clamp or cleat.

The arrangement according to the invention enables the track of the conveyer to be 65 readily and easily adjusted to the conditions of the ground or other working requirements.

What I claim as my invention is:—

1. In a belt conveyer embodying a plurality of movable frames to rest upon the ground and rollers carried by said frames for supporting and guiding a conveyer belt, means for preventing relative movement of said frames, said means comprising a flexible medium and clamping means carried by each of said frames and associated with said flexible medium, all of said clamping means, when said flexible medium is slack, being freely movable lengthwise of the flexible 75 medium and, when said flexible medium is put under tension, engaging said flexible medium to prevent movement of said frames lengthwise thereof.

2. In a belt conveyer embodying a plurality of movable frames to rest upon the ground and rollers carried by said frames for supporting and guiding a conveyer belt, means for preventing relative movement of said frames, said means comprising a flexible medium and means carried by each of said frames through which said flexible medium is movable, each of said last-named means having means forming a bight on said flexible medium, said bight-forming means, 85 when said flexible medium is put under tension, engaging said flexible medium and preventing movement of the flexible medium therethrough.

3. In a belt conveyer embodying a plurality of movable frames to rest upon the ground and rollers carried by said frames for supporting and guiding a conveyer belt, means for preventing relative movement of said frames, said means comprising a channel carried by each of said frames and a flexible member extending through said channels, each of said channels having means permitting the movement of said flexible member therethrough when said 100 flexible member is slack and operative to prevent movement of said flexible member 105 110

therethrough when said flexible member is put under tension.

4. In a belt conveyer embodying a plurality of movable frames to rest upon the ground and rollers carried by said frames for supporting and guiding a conveyer belt, means for preventing relative movement of said frames, said means comprising a flexible member and a channel formed in each of said frames through which said flexible member, when slack, is freely movable, each of said channels having means engaging said flexible member, when tensioned, at a plurality of points to prevent movement of said flexible member through said channel.

5. In a belt conveyer embodying a plurality of movable frames to rest upon the

ground and rollers carried by said frames for supporting and guiding a conveyer belt, means for preventing relative movement of said frames, said means comprising a flexible member and a curved channel extending transversely of each of said frames substantially in the direction of the movement of the conveyer belt and through which said flexible member, when slack, is freely movable, each of said channels being curved in the direction of its length to clamp said flexible member against movement therethrough when said flexible member is tensioned.

In testimony whereof I have signed my name to this specification.

AUSTIN HOPKINSON.
